UNITED STATES PATENT OFFICE.

GEORGE E. TAYLOR, OF ROCHESTER, NEW YORK, ASSIGNOR TO TAYLOR BROTHERS COMPANY, OF ROCHESTER, NEW YORK, A CORPORATION OF NEW YORK.

DESIGN FOR A THERMOMETER-MOUNTING.

SPECIFICATION forming part of Design No. 35,295, dated November 19, 1901.

Application filed September 16, 1901. Serial No. 75,618. Term of patent 7 years.

To all whom it may concern:

Be it known that I, GEORGE E. TAYLOR, a citizen of the United States, residing at Rochester, in the county of Monroe and State of New York, have invented and produced a new and original Design for a Thermometer-Mounting; and I do hereby declare the following to be a full, clear, and exact description of the same, reference being had to the accompanying drawings, forming a part of this specification, and to the reference characters marked thereon.

In the drawings, Figure 1 is a front elevation of a thermometer-mounting embodying my design, and Fig. 2 is a side elevation of the mounting.

Similar reference characters in the two figures indicate similar parts.

The design consists in the general shape and configuration of the mounting and the ornamentation applied thereto.

A indicates a base having the flat surface and the rounded edges *a* and resembling in general form the outline of a bottle. Located on the front of the mounting and at the lower end thereof is an ornamental representation of a bottle in relief, (indicated by B.) A thermometer-tube C is arranged on the base, and the usual degree-markings are arranged opposite the tube, as shown.

The design presents a neat and attractive appearance.

I claim—

The design for a thermometer-mounting, substantially as herein shown and described.

GEORGE E. TAYLOR.
